UNITED STATES PATENT OFFICE

2,428,572

BACKLESS STRAPLESS BRA

Maurice Lobel, San Francisco, Calif.

Application September 28, 1945, Serial No. 619,188

1 Claim. (Cl. 2—42)

1

An object of my invention is to provide a backless, strapless bra which, when worn, will expose the back, shoulders, chest and midriff to the sun's rays so that an even suntan on these portions of the body can be realized. In the usual bra, back straps and shoulder straps are necessary. If these straps are not removed during the exposure of the body to the sun, strap marks are formed on the body. Women bathers have tried to circumvent this by removing the shoulder straps and holding the bra in place by means of their hands. Of course, even when this is done, the back strap cannot be removed.

In my invention, I provide a yielding arcuate-shaped band that encircles the front and sides of the wearer's body at a point directly under the breasts and the ends of the band terminate at places substantially under the shoulder blades of the wearer. This exposes the entire back of the body to the rays of the sun and does away with the necessity of providing a back strap.

The bra is supported by the yielding band that engages with the body with sufficient force to hold the bra securely and firmly in place. If desired the bra may have additional supports that extend upwardly from the body engaging band and hold the bra in proper position. The particular cloth material from which the bra is made may vary in color and shape to create different design appeals.

The device is extremely simple in construction and when not worn may be collapsed into a flat compact bundle so as to be readily transported. The device can be used in connection with bathing suits, sun or play suits, etc.

Other objects and advantages will appear in the following specification, and the novel features of the device will be particularly pointed out in the appended claim.

Figure 1 is a front perspective view of the bra showing it applied to the wearer;

Figure 2 is a rear perspective view of the bra illustrating how the back of the wearer is entirely exposed;

Figure 3 is a front elevation of the bra with the yielding band lying in a flat plane;

Figure 4 is an enlarged section taken along the line IV—IV of Figure 3;

Figure 5 is a vertical enlarged transverse section taken along the line V—V of Figure 3; and

Figure 6 is a plan view of the yielding band showing its general contour.

While I have shown only the preferred forms of my invention, it should be understood that

various changes or modifications may be made within the scope of the appended claim without departing from the spirit and scope of the invention.

5 In carrying out my invention, I provide a yielding band of the shape indicated generally at A in Figure 6. The band has a front portion 1 and arcuate side portions 2 and 3. Figure 5 shows the band A enclosed in a fabric casing B. The casing B is coextensive with the length of the band as shown in Figure 3 and the ends of the casing may be closed by stitching 4 and 5 for entirely enclosing the band. The yielding band may be made of plastic or metal or other flexible material 10 that will bend to hold the shape into which it is bent and then have sufficient elasticity to grip the body when placed on it.

The casing B is U-shaped in cross section and the front and back walls 6 and 7 have their upper 20 edges folded back on themselves to form hems 8 and 9 that are stitched at 10 and enclose the lower edge of a fabric portion C of the bra. The fabric C is preferably of two layers 11 and 12 and it may be of any shape desired. In Figure 3 25 I show the fabric extending from the ends of the casing B and the upper edge is curved as indicated at 13 and 14 to cover the top of each breast. The central portion of the fabric may have a plurality of horizontal gathers as shown by the 30 lines 15 to give a concave curve 16 to the central portion of the upper edge. Vertical rows of stitching 17 at the center of the fabric C will hold the gathered portions 15 in place. I do not wish to be confined to any particular design effect for 35 the bra because the bra can be shaped in various ways.

A flexible strap or ribbon 18 is stitched to the top of the fabric C at 19 and the lower portion 40 of the strap extends through a triangular-shaped opening 20. The free ends of the strap 18 may be brought together in front of the bra and tied to form a bow 21, see Figure 1, so as to create a design appeal. The strap 18 forms no vital part 45 of my invention and may be dispensed with if desired.

The fabric C may have sufficient rigidity or the 50 shaping of the fabric may be such as to hold it in place on the breast without any more support than that afforded by the yielding band A. I add auxiliary supports in the shape of short stays D that may be made of whalebone or a flexible material. The stays D are placed in pockets 22 formed by stitching 23 as shown in Figures 3 and 55 4. The stays D are inclined upwardly and out-

wardly at a slight angle so as to give support to the top of the fabric C adjacent to the curved edges 13 and 14. I have found that the bra is sufficiently supported by the yielding band A and the stays D.

From the foregoing description of the various parts of the device, the operation thereof may be readily understood.

In wearing the device, the band A has its arcuate side portions 2 and 3 swung outwardly so as to receive the body E of the wearer. The band A is positioned on the body so that the fabric C will cover the breast of the wearer. The ends of the band A terminate substantially under the shoulder blades, thus leaving the entire back exposed to the rays of the sun. The stays D give sufficient vertical support to the fabric C so that no neck or shoulder strap is necessary. The yielding band A will hold the bra firmly in place without discomfort.

A bathing suit may have its upper portion provided with the yielding band so that the top of the suit will be supported without the need of neck, shoulder or back straps. It is possible to have the top of the bra supported by a yielding band similar to the band A and have this engage with the body to support the bra top. It is possible to have the ends of the band A project slightly beyond the ends of the casing B to give a more secure support for the bra.

I claim:

A backless strapless bra comprising a yielding preshaped arcuate band adapted to be positioned across the front of the wearer's body just under the breasts, the band having sufficient length to extend around the sides of the body and terminate substantially under the shoulder blades at the back of the body, a breast covering fabric supported by the band and exposing the wearer's neck, shoulders, midriff and substantially all of the back, the band having sufficient resiliency to stay clamped to the body to support itself against accidentally slipping along the body and having sufficient clamping force to support the fabric in a breast-covering position.
